UNITED STATES PATENT OFFICE.

GEORGE H. FORSYTH, OF CHICAGO, ILLINOIS.

METAL WINDOW CONSTRUCTION.

1,053,589.

Specification of Letters Patent.

Patented Feb. 18, 1913.

Application filed June 30, 1906. Serial No. 324,247.

To all whom it may concern:

Be it known that I, GEORGE H. FORSYTH, a citizen of the United States, residing at Chicago, in the county of Cook and State of Illinois, have invented certain new and useful Improvements in Metal Window Constructions, of which the following is a specification.

This invention relates to metal window constructions, and pertains more especially to a novel construction of sash and guiding means therefor, whereby a tight and substantially dust-proof bearing of the sash in its guides is maintained.

15 The invention has been more particularly although not exclusively, designed for use in connection with car windows. In carrying out the main feature, which pertains to the sash-guiding means, I provide in the 20 stiles or other guide-engaging members of the sash seats or pockets adapted to contain one or more auxiliary guiding devices, such as balls or rollers; said seats or pockets in some forms being provided with an inclined 25 wall against which the ball or roller bears, the other side of said ball or roller bearing against the bottom or side wall of the guide-groove, whereby the ball or roller exerts a wedging action tending to produce a snug 30 fit of the stile or other guide-engaging member in the guide-groove. Where the said ball or roller operates as a wedge I provide means whereby its wedging action may be wholly or partially intermittent when the 35 window is to be raised or lowered, so as to permit a free sliding action of the sash in its guides. In other forms of the invention, a ball or corresponding member may be caused to maintain a substantially uniform 40 and preferably elastic engagement between the sash and its guide or guides, and to co-operate in guiding the sash during movement.

The invention will be readily understood 45 when considered in connection with the accompanying drawing, showing an approved mechanical embodiment thereof, in which,—

Figures 1 to 6, inclusive, are end views of a sash stile and its co-operating guide-groove, showing various forms and applications of my invention thereto; Figs. 7 and 8 are fragmentary cross-sectional views on lines 7—7 and 8—8 of Fig. 1, respectively; Fig. 9 is an elevation of the lower 55 end of a sash, illustrating a simple ball-releasing means; and Fig. 10 is a detail per-

spective view of an attachable ball-engaging strip employed in one of the forms of the invention illustrated.

Referring to the drawings, 15 may designate in Figs. 1 to 7 a portion of the casing having formed integrally therewith or secured thereto side and bottom walls 16 and 17, respectively, of usual sash-guiding grooves.

18 designates as an entirety a detachable strip secured to the casing 15 the inner wall of said strip constituting in various forms hereinafter more particularly referred to, the opposite side wall of the guide-groove.

19 designates a ball constituting a feature common to all of the several specific embodiments of the invention illustrated; which ball is interposed between one or more surfaces of the guide-groove and one or more adjacent surfaces of the sash frame, and has for its main functions to hold the sash in engagement with the guide-groove, to co-operate in guiding the sash, to adjust the sash widthwise of the opening, and, in some forms, to substantially lock the sash in any open or closed position, except when released by an actuating mechanism herein-after described to permit the moving of the sash. These several functions are effected in the several forms shown by causing the ball to engage between bearing surfaces of the sash and guide, respectively, one of which is either resilient or inclined to the other, or both.

Referring now more particularly to the specific structure of the several forms shown, and considering first the construction illustrated in Figs. 1, 7 and 8, 20 designates a hollow sheet metal sash frame member, herein shown as a stile, in one of the side walls of which is formed a shallow recess or pocket 21 which may conveniently be created by stamping or pressing the metal inwardly by means of a suitably shaped die, 100 as shown, or by riveting a separate piece to the sash. This pocket is deepest at its center and of gradually increasing shallowness toward its ends, as best shown in Fig. 8. In this pocket is placed the ball 19, one 105 side of which ball has a rolling engagement with the inner wall of the pocket, while its other side rollingly contacts the inner wall of the guide-strip 18, which inner wall may be bent or otherwise formed to present a 110 shallow V-groove running lengthwise of the strip, as shown at 22 (Fig. 1). It will be

apparent that by virtue of this construction the ball tends by gravity to wedge and crowd itself into the lower end of the pocket 21, whereby it tends to crowd the sash stile 23 transversely and maintain the opposite side of the stile in snug engagement with its contacting wall 16 of the groove, and to hold the sash laterally in its guides. It will also be apparent that any lifting effect upon the sash will tend to roll the ball farther down in the pocket, thus increasing the transverse crowding effect and tending to lock the sash against a lifting movement.

In Fig. 2 the sash stile 23 has the longitudinal marginal portions of its two side walls inwardly turned at an angle to each other, as indicated at 24, from each of which marginal portions are formed horizontal upper and lower lips 24^a serving to confine the ball against vertical movement. One side of the ball contacts the members 24 between the upper and lower lips 24^a, while the opposite side of the ball has rolling engagement with a shallow V-groove 22^a formed in and longitudinally of the inner or bottom wall 17 of the groove. The inturned margins 24 are resilient and tend to force the ball against the groove 22^a, this action also tending, by reaction, to force the sides of the stile against the side walls of the groove.

In the construction shown in Fig. 3 the sash stile 25 has one of its side walls formed with an inwardly bent angular marginal strip 26, in which latter is formed a pocket 21^a similar to the pocket 21 already described; said pocket having rolling engagement with one side of the ball 19, the latter having a rolling engagement on its opposite side with the bottom wall 17 of the guide-groove and also with the inner side of the opposite side wall of the sash stile. This construction, like that of Fig. 2, tends to spread the side walls of the stile and maintain them in snug engagement with their respective adjacent walls of the groove.

Figs. 4 and 10 show a construction employing a hollow sheet metal stile 27 generally similar to the stile 20 of Fig. 1; one corner of said stile being flattened so as to to present a transversely inclined wall 28, to which latter is secured a ball-retaining strip having a horizontal lip 29 overlying the ball and an inclined tongue 29^a oblique to the plane of the sash extending beneath the ball, so as to throw out the latter; which tongue may be of elastic metal. This tongue 29^a fills the same office and serves the same purpose as the lower inclined portion of the pocket or seat described in connection with Figs. 1, 7 and 8. Said ball also engages at one point the bottom wall 17 of the guide-groove, while the guide-strip 18 has its inner face formed to present a wide angle 29^b (transversely of the strip) one or both of the surfaces of which may rollingly contact

the ball. In this construction the wedging effect of the ball tends to crowd the sash laterally in an oblique direction, one component of which crowds the sash cross-wise of its guide-groove, while the other component tends to crowd the sash widthwise or in its own plane. The arrangement shown is adapted for a counter-balance sash; for a gravity sash the strip would be inverted.

In the construction shown by Fig. 5 the bottom wall 17 of the groove has formed therefrom horizontal ball confining lips 17^a, and the ball engages the inclined wall 28 of the sash, being thrown into such engagement by the pressure thereon of a free inwardly turned elastic marginal portion 30 of the strip 18.

Fig. 6 shows a modification of the construction of Fig. 3, wherein one of the side walls 31 of the sash stile is somewhat narrowed so as to just enter the groove without being engaged by the ball 19, the latter engaging the bottom wall 17 of the groove and an elastic marginal portion 32 of the guide-strip 18; the effect secured by this construction being substantially the same as that pertaining to the construction of Fig. 3.

It will be observed that in all the constructions thus far described excepting that of Fig. 1, the deflected walls with which the ball contacts are inclined to horizontal lines both in the plane of and transverse to the plane of the sash and as a consequence the action of the ball is to thrust the sash both in a crosswise and edgewise direction. This latter is of especial advantage where the construction described is employed only upon one stile of the sash, as it tends to force the corresponding edge of the opposite stile into closer engagement with the bottom wall of its co-operating guide-groove.

For the purpose of raising the ball out of the bottom of the socket so as to release or relieve the wedging action when the sash is to be raised, I show in Figs. 7, 8 and 9 a strip 33 mounted in suitable guides 34 within the stile, said strip having a horizontal arm 35 projecting through the side wall of the pocket so as to lie beneath the ball, for which purpose said side wall is provided with a vertical slot 36. The lower end of the strip 33 projects through a slot in the side of the sash, forming a handle 37, by raising which the ball may be contacted and raised by the arm 35 to a free position. A spring 38 normally forces the strip downwardly to a position in which the arm 35 lies below the lowest position assumed by the ball 19. The strip 33 may also be provided with another arm 39 also projecting through the slot 36 above the ball, so that by depressing the handle 37 the ball may be forced downwardly to increase the wedging effect. The construction last described is for a counter-balanced sash; in the case of 130

a gravity sash the spring 38 would act in the opposite direction, and the functions of the arms 35 and 39 would be reversed. This device may, obviously, be applied, with 5 slight change of relative location, to all of the several forms shown in Figs. 2 to 6, inclusive.

It will be evident to those skilled in the art that various features of the invention 10 as above described and shown in the drawing may be considerably modified and varied without departing from the principle of the invention or sacrificing any of the advantages thereof. Hence I do not limit the 15 invention to the particular construction shown, except to the extent indicated in specific claims.

I claim—

1. The combination with a sash and sash 20 guide, of a surface on one of said parts inclined to horizontal lines both in the plane of and transverse to the plane of the sash, a wedge member interposed between said inclined surface and an opposed surface on 25 the other of said parts, and a release for said wedge member mounted on said sash, substantially as described.

2. The combination with a sash and sash 30 guide, of a surface on one of said parts inclined in a direction transverse to the plane of the sash, a roll interposed between said inclined surface and an opposed surface on the other of said parts, and releasing means 35 mounted on said sash and adapted to move said roll thereby permitting free movement of the sash within the sash guide, substantially as described.

3. The combination with a sash and sash 40 guide, of a surface on one of said parts inclined to horizontal lines both in the plane of and transverse to the plane of the sash, a wedge member interposed between said inclined surface and an opposed vertical surface on the other of said parts, and means 45 for releasing said wedge member thereby permitting free movement of the sash, substantially as described.

4. The combination with a sash and sash 50 guide, of a surface carried by said sash and inclined to horizontal lines both in the plane of and transverse to the plane of the latter, a wedge member interposed between said inclined surface and an opposed vertical sur-

face of the guide, and a manually actuated release mounted on said sash for releasing 55 said wedge member thereby allowing free movement of the sash, substantially as described.

5. The combination with a sash and sash 60 guide, of relatively yieldable surfaces carried by said parts disposed at an angle to each other and yieldable in a direction transverse to the plane of the sash, and a wedge member interposed between said surfaces, substantially as described. 65

6. The combination with a sash and a sash 70 guide, of a sash-adjusting device comprising a pair of relatively inclined surfaces carried by said parts, the inclination whereof lies in a direction oblique to the plane of the sash, and a wedge member between and yieldable relatively to said surfaces, substantially as described.

7. The combination with a sash and a 75 sash guide, of relatively inclined surfaces carried by said parts, and means between and co-operating with said surfaces and brought into action by the movement of the sash, normally tending to thrust the sash both edgewise in its own plane and transversely into engagement with a side wall of the guide, substantially as described.

8. The combination with a sash and a 80 sash guide, of inclined surfaces carried by said parts disposed at an angle to each other, a roll member interposed and acting between said inclined surfaces, and means 85 mounted on the sash for releasing said roll thereby allowing free movement of the sash within the sash guide, substantially as described. 90

9. The combination of a sash and sash 95 guide, of a surface on one of said parts inclined to horizontal lines both in the plane of and transverse to the plane of the sash, tightening means interposed between said inclined surface and an opposed surface on the other of said parts, and means carried by said sash for releasing said tightening means, thereby permitting free movement of 100 the sash, substantially as described.
